UNITED STATES PATENT OFFICE.

WILLIAM F. STERN, OF DETROIT, MICHIGAN, ASSIGNOR OF ONE-HALF TO JOHN R. LITTLE, OF SOUTH MILWAUKEE, WISCONSIN.

STEAM BOILER.

1,424,322.

Specification of Letters Patent. Patented Aug. 1, 1922.

Application filed April 26, 1920. Serial No. 376,761.

To all whom it may concern:

Be it known that I, WILLIAM F. STERN, a citizen of the United States, residing at Detroit, in the county of Wayne and State of Michigan, have invented certain new and useful Improvements in Steam Boilers, of which the following is a specification.

This invention relates to steam boilers, and the primary object of the invention is to provide an improved boiler having a relatively large area of heating surface and in which a small quantity of water is required to develop and maintain a steady pressure of steam.

Another object of the invention is to provide an improved vertical boiler in which the parts thereof are compactly arranged so that the same can be effectively used in spaces of a limited area.

A further object of the invention is to provide a vertical boiler having an improved means for preheating the water prior to the entrance thereof into the steam generating section thereof, so as to prevent the cracking of the boiler by the sudden lowering of the temperature thereof when water is introduced into the same.

A further object of the invention is to provide an improved means for circulating the heated air around the portions of the boiler containing the water to be generated into steam, so that the water will be quickly turned into steam and thereby permit the use thereof a short time after the burner has been lit.

A still further object of the invention is to provide an improved steam boiler of the above character which is durable and efficient in use, one that is simple and easy to manufacture, and one which can be placed upon the market at a reasonable cost.

With these and other objects in view, the invention consists in the novel construction, arrangement and formation of parts as will be hereinafter more specifically described, claimed and illustrated in the accompanying drawings, forming a part of this invention, in which drawings:

Figure 1 is a vertical longitudinal section through the improved steam boiler.

Figure 2 is a horizontal section taken on the line 2-2 of Figure 1.

Figure 3 is a bottom plan view of the same.

Referring to the drawings in detail, wherein similar reference characters design-

ate corresponding parts throughout the several views, the letter A generally indicates the improved boiler which includes the outer casing 5, the water reservoir 6 and the steam generating portion 7.

60

The steam generating portion 7 includes a plurality of concentrically arranged cylindrical members, 8, 9 and 10 each of which includes cylindrical walls 11 connected by upper and lower heads 12. While three concentric cylindrical members are shown, it is to be understood that any number of the same may be provided as is desirable or practical according to the use to which the boiler is to be put. The members 8, 9 and 10 are arranged in spaced relation so as to permit the products of combustion or the heated air to rise up between the same and thereby readily heat the water therein. The section 10 is connected with the section 9 at diametrically opposed points at its upper end by pipes 13, which serve as means for conducting the steam generated in the inner section 10 to the intermediate section 9. The section 9 is connected to the outer section 8 by means of diametrically opposed pipes 14 and these pipes 14 are arranged intermediate the pipes 13 and form means for conducting the steam in the upper portion of the section 9 to the outer section 8. The lower end of the central section 10 is connected to the section 9 by means of pipes 15 and these pipes are arranged below and intermediate the pipes 13 and serve as means for conducting water from the intermediate section 9 to the inner section 10. The intermediate section 9 is connected at its lower end to the outer section 8 by means of the pipes 16 which are arranged intermediate the pipes 15 and intermediate and below the pipes 14 and these pipes serve as means for conducting water from the lower end of the section 8 to the lower end of the intermediate section 9. The pipes 13, 14, 15 and 16 not only serve as means for supplying water to the sections and for conveying steam from the sections, but also serve as means for connecting the sections together and for holding the same in their correct spaced relation and the arrangement of these pipes is such that the strain is equally distributed to all portions of the sections. While the sections 8, 9 and 10 of the steam generating portion 7 of the boiler are shown circular in formation, it is

105

serve as means for conveying steam from the sections, but also serve as means for connecting the sections together and for holding the same in their correct spaced relation and the arrangement of these pipes is such that the strain is equally distributed to all portions of the sections. While the sections 8, 9 and 10 of the steam generating portion 7 of the boiler are shown circular in formation, it is to be understood that the same can be of any 110

configuration, that is, square, oval or rectangular shaped in cross section. The outer water reservoir 6 is of the same configuration as the steam generating portion 7 of the boiler and completely surrounds the same and is arranged in concentric spaced relation thereto. The lower end of the water reservoir extends below the steam generating portion 7 of the boiler and forms in connection with the steam generating portion 7 a housing for the heat producing means, such as a gas burner 17. The outer water reservoir 6 consists of inner and outer spaced side walls 18 and 19 and upper spaced walls 20. The inner side wall 18 has its lower end curved inwardly as at 21 in engagement with the lower surface or edge of the outer side wall 19 and this forms a complete water housing between the inner and outer side walls 18 and 19 and the upper spaced walls 20. The curvature of the lower end 21 of the inner side wall 18 also forms means for deflecting the heat from the burner upwardly between the air spaces between the water reservoir 6 and the steam generating portion 7. The upper spaced walls 20 of the water reservoir 6 are arranged above the upper ends of the sections 8, 9 and 10 of the steam generating portion 7 of the boiler and form the means for directing the heated air over the upper surface of the sections. The upper walls 20 are connected by a central nipple 22 which form means for permitting the escape of the gases from the upper end of the boiler. The lower plate of the upper wall 20 has connected thereto the depending pipe 23, which communicates with the interior of the water reservoir, and this pipe extends downwardly into the outer section 8 of the steam generating portion 7 and as the water in the reservoir reaches the upper portion thereof the same gradually overflows into the pipe 23 and into the outer section 8 which supplies the water to the other sections. The pipe 23 is connected as at 24 to the outer section and forms means for holding the steam generating portion in correct relation to the water reservoir.

The outer casing 5 completely surrounds the water reservoir 6 and the steam generating portion 7 and is shaped according to the configuration of the steam generating portion 7 and the water reservoir 6 and, as shown, is circular in cross section and includes the outer cylindrical side wall 25 and the top circular wall 26. The side wall 25 and the top wall 26 are arranged in spaced relation to the water reservoir and the heat and gases flowing through the nipple 22 enter into the space between the water reservoir and the casing 5 and flow down around the water reservoir and out of a pipe 27 which is provided for that purpose. The water reservoir 6 has communicating therewith adjacent to its lower end a water sup-

ply pipe 28 which extends outwardly through the casing 5 and it can be seen that as the water enters the water reservoir 6, the same is heated by the passage of the heated air and gases between the outer section 8 of the steam generating portion 7 and the water reservoir 6 and around and between the water reservoir and the outer casing 5. As the water is heated it gradually rises into the upper wall 20 of the water reservoir and flows into the pipe 23 and down into the outer section 8 of the steam generating portion 7 where it is distributed by means of the pipes 15 and 16 through the intermediate and inner sections 9 and 10. The passage of the heated air and gases between the sections 8, 9 and 10 of the steam generating portion 7 heats the water and turns the same into steam which is delivered to the outer section 8 by means of the pipes 13 and 14. A steam outlet pipe 30 is secured to and communicates with the outer section 8 as at 31 and this pipe extends through a nipple 32 carried by the plate 20 of the upper wall of the water reservoir and out of the upper wall 26 of the casing 5. The pipe 30 is secured to the upper wall 26 of the casing 5 as at 33 and this pipe also forms means for retaining the steam generating portion 7 in correct relation to the water reservoir. A water gauge 34 of the usual or any preferred configuration is provided for the boiler so that the height of the water in the steam generating portion 7 can be readily determined at all times and the water gauge is connected by means of upper and lower pipes 35 with the section 8 of the generating portion 7 and the height of the water can be readily seen in the glass column 36 which may be graduated if so desired. A suitable hand operated valve 37 is also provided for cutting off the water from the gauge when necessary. A drain cock 38 is also provided for the gauge. The upper end of the gauge 34 supports a steam pressure gauge 39 and thus the pressure of the steam in the steam generator 7 can be readily seen. The pipes 35 of the gauge 34 also tend to hold the steam generating portion in correct position. A drain pipe 40 communicates with the lower end of the outer section 8 of the steam generating portion 7 and extends outwardly of the casing 5 and is connected thereto as at 41. This drain pipe serves as means to drain all water and sediment from the steam generating portion when necessary or desirable. This pipe also forms means for holding the steam generating portion 7 in correct position.

To facilitate the cleaning of the boiler the removable hand holds 42 and 43 are provided for the outer casing 5 and the water reservoir 6.

From the foregoing description it can be seen that an improved vertical boiler is

provided in which the water is effectively preheated before the entrance thereof into the steam generating portion and in which the steam generating portion and the water reservoir is so arranged that a maximum area of heating surface for both of the same is provided.

Changes in details may be made without departing from the spirit or scope of my invention; but,

I claim:

1. In a steam boiler, the combination of steam generator sections arranged in equi-distantly spaced relation to each other, means for establishing communication between said sections, a water reservoir arranged in spaced relation to the steam generating sections and completely surrounding the same, a casing surrounding the water reservoir and arranged in spaced relation thereto, a burner arranged below the steam generating portions and housed by said water reservoir, means for supplying water to the water reservoir, a depending pipe carried by the upper end of the water reservoir and extending into one of said sections, a gas and hot air outlet formed in the upper end of said water reservoir, and a gas and hot air outlet formed in the lower end of said casing.

2. In a steam generating boiler, the combination of a plurality of equi-distantly spaced concentrically arranged steam generating sections, steam pipes connecting the inner section to the intermediate section at diametrically spaced points at the upper ends of said sections, steam pipes connecting the intermediate sections to the outer sections at diametrically spaced points and arranged intermediate the first mentioned steam pipes, water pipes connecting the lower ends of the inner section to the intermediate section at diametrically spaced points, water pipes connecting the lower ends of the intermediate section with the outer section at diametrically spaced points and arranged intermediate the first mentioned water pipes, a water reservoir surrounding said steam generating sections and arranged in concentric relation thereto, means for supplying water to the lower end of said reservoir, a depending pipe carried by the upper end of said reservoir and communicating with the outer steam generating section, a housing surrounding said water reservoir and arranged in spaced concentric

relation thereto, a burner arranged below said steam generating sections and enclosed by said water reservoir, a hot air and gas outlet formed in the central portion of the water reservoir at the upper end thereof, a hot air and gas outlet formed in the casing at the lower end thereof, and a steam outlet formed in the upper end of the outer steam generating section.

3. In a steam generating boiler, the combination of a plurality of equi-distantly spaced concentrically arranged steam generating sections, a water reservoir completely surrounding said sections and arranged in concentric spaced relation thereto, means connecting the steam generating sections together, a steam outlet pipe communicating with the steam generating sections, a casing surrounding the water reservoir and arranged in concentric spaced relation thereto, means for supplying water to the water reservoir, means for introducing water from the water reservoir into the steam generating sections, a burner arranged below said steam generating sections and enclosed by said water reservoir, the inner wall of said water reservoir adjacent to the lower end thereof being inclined inwardly to direct heated air and gases towards said steam generating sections, a water and steam gauge for said steam generating sections, and means for draining the water from said steam generating sections when so desired.

4. A steam generating boiler comprising a vertically disposed cylindrical steam generating section having a flue therethrough and intermediate and outer cylindrical steam generating sections surrounding the first mentioned steam generating section and arranged in spaced concentric relation therethrough, water and steam conducting stay pipes connecting the upper and lower ends of the steam generating sections together, a casing housing said sections, a water reservoir arranged in said casing for receiving said steam generating sections, and a water feed pipe communicating with the lower end of the reservoir, a water outlet pipe carried by the water reservoir extending into the outermost of the steam generating sections, means for permitting the flow of heated air into the casing, and means for permitting the exit of the heated air from the lower end of the casing.

WILLIAM F. STERN.
